FREQUENCY MODULATION SIGNAL SYSTEM

Wendell L. Carlson, Haddonfield, N. J., assignor
to Radio Corporation of America, a corporation
of Delaware

Application August 29, 1941, Serial No. 408,867

3 Claims. (Cl. 250—6)

This invention relates to frequency modulation signal systems, and has for its primary object to provide an improved system of the character referred to, for wide frequency band operation at ultra high frequencies.

It is a further object of this invention, to provide an improved frequency modulation signal system which operates with compound modulation, including a sub-carrier frequency signal for frequency modulating a main carrier frequency signal, and a second modulating signal, such as sound in the audio frequency band, for frequency modulating the sub-carrier frequency signal, thereby to provide an improved signal to noise ratio at the receiving end of the system.

It is an object of this invention, furthermore, to provide an improved multiple or compound frequency modulation signal system providing at least two modulating signals, one of which is a sub-carrier frequency signal, and a simplified and effective receiving system for said signals including a narrow band $i-f$ amplifier for the sub-carrier frequency signals.

In a system embodying the invention, a sub-carrier frequency signal is frequency modulated with an audio frequency or other modulating signal, and a main carrier frequency signal is frequency modulated with the modulated sub-carrier frequency signal, and the deviation frequency swing for either or both of the modulation signals is made of the order of or greater than the modulation frequencies employed.

Further in accordance with the invention, a receiving system for multiple or compound frequency modulation may include conventional radio frequency or ultra high frequency input circuits including a heterodyne converter and local oscillator, and wide band first intermediate frequency amplifier circuits, followed by a sub-carrier detector with or without a preceding limiter. The output circuit from the sub-carrier detector is coupled to a second or sub-carrier intermediate frequency amplifier of reduced band width and an audio frequency detector which may or may not be preceded by a limiter. Both detectors are for frequency modulated signals.

The invention will be further understood from the following description, when considered in connection with the accompanying drawings, and its scope is pointed out in the appended claims.

In the drawings, Figure 1 is a block circuit diagram of a transmitter for producing multiple or compound frequency modulation signals for

reception and selection in accordance with the invention;

Figure 2 is a similar schematic block circuit diagram of a multiple frequency modulation signal receiving system arranged in accordance with the invention; and

Figures 3 to 6, inclusive, are graphic diagrams illustrating the operation of the system of Figs. 1 and 2 with different sub-carrier frequency signals and deviation frequency bands for the main and sub-carrier frequency signals.

Referring to Fig. 1, a sub-carrier oscillator 5 which may operate at any suitable sub-carrier frequency, for example, between 25 and 100 kc., 15 is coupled to a first frequency modulator 6 to which is applied a modulating signal from a source comprising a microphone 7 and an audio frequency amplifier 8, in the present example. The sub-carrier oscillations are modulated by 20 sound from the microphone 7, amplified through the amplifier 8, and applied to the modulator 6 with any desired total frequency deviation or swing, for example, between 20 kc., and 150 kc. This may represent a relatively wide deviation 25 frequency band or swing with respect to the frequency of the modulating signal, which may be in the normal audio frequency band between 50 and 10,000 cycles.

The frequency modulated sub-carrier signal 30 is amplified in a suitable amplifier indicated at 9, and is applied to a second frequency modulator 10 along with a carrier signal which is derived from a main carrier oscillator, indicated at 11. The multiple frequency modulated signal 35 is then applied to suitable radiating means 12 after amplification in a power amplifier or other amplifying indicated at 13.

The frequency modulation of the main carrier signal by the sub-carrier may have a deviation 40 frequency band or swing of the order of or greater than the frequency of the sub-carrier signal. This total deviation, excluding the modulation deviation on the sub-carrier, may be of the order of from 100 kc. to 600 kc., for example, 45 as will hereinafter be pointed out. Thus the deviation frequency swing for either or both of the modulating signals may be greater than the modulating frequency employed and greatly improves the signal-noise ratio at the receiving end of the 50 system.

When the transmission and reception is carried out at ultra high frequencies of the order of 100 mc. or higher, a wider pass band may be utilized in the receiving system for the main carrier with much less critical tuning for best noise

reduction. The line-up of the circuits is facilitated and is less critical, because the band width for the main carrier, and its modulation frequencies, is relatively large compared with that for the sub-carrier frequency, and its modulation frequencies.

The correct tuning of the signal to the sub-carrier amplifier and its discriminator is a function of the transmitter sub-carrier frequency and the initial adjustments of the receiver sub-carrier circuits, and is independent of inaccuracies in the input tuning adjustment and the frequency drift of the local oscillator.

In the present example, it may be assumed that the main carrier or the transmitted signal is of the order of 500 mc., this being the center frequency.

At the receiver, one example of which is shown in Fig. 2, the ultra high frequency signals are collected by a suitable antenna, such as a dipole 15, and received in suitable conventional input or *r-f* circuits represented by an *r-f* amplifier 16, a heterodyne converter 17, and a local oscillator 18, coupled as schematically indicated, to produce the usual intermediate frequency signal for amplification in an intermediate frequency amplifier 19.

The amplifier 19 is of the wide band type having a pass band of from 200 to 800 kc., that is, so as to pass a frequency band equal to the transmitted frequency band.

The main carrier intermediate frequency amplifier is followed by a suitable discriminator and detector 20, with a limiter 21 interposed between the carrier *i-f* amplifier and discriminator and detector, if desired.

The detector 20 is followed by an amplifier 22 responsive to the sub-carrier intermediate frequency and having a relatively narrow frequency band or pass band characteristic with respect to that of the carrier *i-f* amplifier, and in any case under the present assumed values, this band may be of the order from 30 to 200 kc., with a mean or center frequency for the sub-carrier of from 25 to 100 kc.

The remainder of the receiving system may be conventional in that it may include a second discriminator and audio frequency detector 23 preceded by a limiter 24 and followed by a suitable audio frequency amplifier 25 and output device such as a loudspeaker 26 for reproducing the initial modulation frequencies or signal.

Referring to Figs. 3 to 6, along with Figs. 1 and 2, in the frequency arrangement illustrated in Fig. 3, the pass band of the first or carrier intermediate frequency amplifier is of the order of 200 kc. and the main carrier is frequency modulated by the sub-carrier frequency with a maximum swing or frequency deviation of 50 kc. on either side of the mean or center frequency of 500 mc., while the sub-carrier frequency of 50 kc. is frequency modulated by audio frequency signals with a maximum frequency deviation or swing of 25 kc. on either side of its center frequency.

A guard band of 25 kc. is provided on either side of the main frequency modulated signal, thus making the pass band of the first or main carrier intermediate frequency amplifier of the order of 200 kc. as above noted, and the pass band of the sub-carrier or second intermediate frequency amplifier of the order of 100 kc.

In the example shown in Fig. 4, the main carrier is frequency modulated by the sub-carrier frequency with a maximum frequency deviation

of 200 kc. A sub-carrier frequency of 100 kc. is employed, which, in turn, is frequency modulated by the audio frequency signal with a maximum frequency deviation or swing of 150 kc. The guard band is retained at 25 kc. This causes the overall or pass band of the main carrier intermediate frequency amplifier to be of the order of 400 kc., while the sub-carrier intermediate frequency amplifier provides a pass band of the order of 200 kc.

In the example shown in Fig. 5, the main carrier is widely modulated with a maximum frequency deviation or swing of the order of 600 kc., by the sub-carrier, while the sub-carrier of 100 kc. is frequency modulated in the same manner as for Fig. 4 with a maximum frequency swing of 150 kc. in response to the audio frequency modulation, and the guard band is the same. The total frequency band, including the modulation and guard bands is 800 kc. in that case.

It is preferable that one of the deviation frequencies exceeds while the other is less than the modulating frequency as in the example of Fig. 4. For example, with the same wide swing frequency modulation of the main carrier as in the example of Fig. 5, the sub-carrier frequency may be reduced to 25 kc., and it may be frequency modulated by the audio frequency signal within the narrow range of 20 kc. and with a pass band of only 30 kc. for the second *i-f* amplifier, as indicated in Fig. 6. With this arrangement, the first intermediate frequency amplifier may have a pass band of the order of 700 kc. with wide range modulation of the main carrier and with a high degree of selectivity for the narrow band sub-carrier *i-f* amplifier, resulting in an improved signal-to-noise ratio.

The different frequency combinations illustrated in the graphs comprising Figs. 3 to 6 are only given by way of example of the various combinations which may be employed for satisfactory results in a compound or multiple frequency modulation system embodying the invention.

It has been found that with this system, signal to noise ratios of a relatively high order are obtained which are superior to conventional double amplitude or amplitude and frequency modulation systems. This is true under various conditions of operation, including response on weak impulse noise or strong impulse noise. The line-up tuning of the sub-carrier and second discriminator circuits are not critical. With an increase in band width, the signal to noise ratio improves more rapidly than in direct proportion to the band width and with wide band reception of the main carrier and narrow band reception of the sub-carrier, the tuning is not as critical for maximum noise reduction as in conventional frequency modulation systems.

I claim as my invention:

1. The method of communicating by a radio signal which comprises producing a frequency-modulated wave, the frequency of which is above one hundred megacycles for wide band modulation, producing a frequency-modulated sub-carrier high frequency signal, frequency modulating the main carrier with said sub-carrier frequency signal, the deviation frequency swing of said frequency modulated wave exceeding the center frequency of the frequency modulated sub-carrier signal, and the deviation frequency swing of the sub-carrier frequency signal being less than the maximum modulating frequency, amplifying and demodulating the main carrier wave

in a relatively wide frequency band, and amplifying and demodulating the sub-carrier frequency signal in a relatively narrow frequency band of the order of twice the value of the maximum modulating frequency.

2. A radio signal receiving system for frequency modulated main and sub-carrier frequency signals, comprising signal input circuits and a main carrier intermediate frequency amplifier providing a frequency pass band substantially equal to the transmitted frequency band, a second intermediate frequency amplifier connected with said first intermediate frequency amplifier responsive to the sub-carrier intermediate frequency and having a pass band of less than twice the highest initial modulating frequency, a frequency discriminator and detector interposed between said intermediate frequency amplifiers for deriving the frequency-modulated sub-carrier signal, and a second frequency discriminator 20

and detector coupled to said second intermediate frequency amplifier for deriving the modulation signal.

3. An ultra high multiple frequency-modulation signal system comprising in combination, 5 means providing a modulating signal, means providing a high frequency sub-carrier modulating signal, means providing an ultra high frequency main carrier wave, means for frequency modulating the main carrier wave with the sub-carrier signal providing a deviation frequency swing at least of the order of 10:1 with respect to the sub-carrier center frequency, and means for frequency modulating the sub-carrier frequency signal with said modulating signal with a deviation frequency swing substantially of the order of the highest frequency of the first mentioned modulating signal.

WENDELL L. CARLSON.
